Primary Examiner — Cynthia R Underwood(74) *Attorney, Agent, or Firm* — Lee & Hayes, P.C.(57) **CLAIM**

The ornamental design for an electronic device adapter, as shown and described.

DESCRIPTION

FIG. 1 is a front perspective view of an electronic device adapter;

FIG. 2 is a back perspective view thereof;

FIG. 3 is a top view thereof;

FIG. 4 is a bottom view thereof;

FIG. 5 is a left-side view thereof;

FIG. 6 is a right-side view thereof;

FIG. 7 is a front view thereof; and,

FIG. 8 is a back view thereof.

The dashed broken lines depict portions of the electronic device adapter that form no part of the claimed design.

1 Claim, 7 Drawing Sheets(56)
